UNITED STATES PATENT OFFICE

CHARLES D. BONSALE, OF NEW KENSINGTON, PENNSYLVANIA, ASSIGNOR TO P. H. MURPHY COMPANY, OF NEW KENSINGTON, PENNSYLVANIA, A CORPORATION OF PENNSYLVANIA

CARLINE REINFORCEMENT AND LOAD-LIFTING ARRANGEMENT

Original application filed March 8, 1926, Serial No. 93,155. Patent No. 1,645,217, dated October 11, 1927.
Divided and this application filed May 3, 1927. Serial No. 188,565.

In some cars the roof structure comprises carlines spanning the distance between the opposite side plates with metallic roof sheets spanning the spaces between the adjacent carlines. These roof sheets are sometimes secured to the carline making what is known as a rigid steel roof and sometimes positioned loosely between the carlines making what is known as a flexible steel roof. In such types of roofs the bottom of the carlines are substantially flush with the bottom of the roof sheets, thus obtaining a flat interior surface. With such roofs it is frequently impossible to secure a rope or chain to the carline or in fact to any other part of the roof, therefore, it is difficult and cumbersome to move heavy ladings into, out of or around in the car.

My invention resides in reinforcing all, or some of the carlines of an all metal car roof by means which also constitute a support for longitudinally extending beams, which beams are used for attaching loading devices.

The beams extend longitudinally of the car and may span the distance between two adjacent carline reinforcements or three or more carlines or, in fact, may effectively extend the full length of the car. The beams may be positioned in parallel pairs, as shown in Fig. 1, or in parallel pairs in combination with single beams, as shown in Fig. 2, or in staggered relation, as shown in Fig. 3, or they may be positioned in alignment. Various arrangements and combinations of the carline reinforcements and beams may be devised to suit the requirements of the railroads and shippers.

The invention reinforces the individual carlines to sustain vertical loads; obtains co-operation between the adjacent carlines to sustain horizontal loads; reinforces the roof framing against distortion in a horizontal plane. The means connecting the adjacent carlines are also beams and provide a place to attach a block and tackle or rope to raise the lading. These connecting means or beams extend longitudinally of the car so as to provide a large range of operation which is particularly advantageous if the lading

is long, such as automobiles or rails; furthermore, the weight of the sustained lading is distributed to at least two reinforced carlines.

The end plate is the end carline of a railway car for all intents and purposes of this invention, therefore, no distinction is made in the claims herein.

In the drawings:

Figs. 1, 2 and 3 are diagrams showing various arrangements of applying the device to a railway car as already explained.

Fig. 4 is a partial cross section of a roof of a car with my device applied thereto.

Fig. 5 is a section on line 5—5 of Fig. 4. 65

Fig. 6 is a section on line 6—6 of Fig. 5.

Fig. 7 is a section on line 7—7 of Fig. 5.

Fig. 8 is a section on line 8—8 of Fig. 5.

In the drawings I have shown a so-called "all steel" metallic roof comprising a plurality of sheets 2 spanning the distance between the opposite side plates 3 of the car and secured thereto. Each sheet is provided with an upstanding flange 4 at each opposite side and each flange is positioned near a corresponding flange on the adjacent sheet. A carline cap 5 is provided which straddles the flanges of the adjacent sheets and rivets 6 secure the flanges and the carline-cap together. These carline-caps are positioned above the roof sheets and outside of the car so that they do not occupy any of the loading space within the car. This carline-cap 5 is made of sufficient thickness of material and depth to provide the required strength to enable it to perform the functions of a carline without any additional members or reinforcements. The carline-cap is preferably provided with oppositely projecting flanges 7 which increase its strength to sustain a vertical load and also provide means (8) for attaching the carline-cap to the side plates of the car.

While I have specifically described one type of roof, it is understood that my device may be applied to other types of car roofs and I intend to file other applications for patents covering the means and constructions for adapting the device thereto.

When it is desired to apply my device to a 100

carline in the type of roof described, a web plate 10 is inserted between the flanges 4—4 of adjacent roof sheets and secured thereto by the same rivets or other means which hold the flanges and carline-cap together. This web plate is preferably horizontal along its lower edge 11 so as to obtain the maximum strength and greatest clearance between the roof sheets and the beams without reducing the loading capacity of the car.

10 Loading beams 12 extending longitudinally of the car are positioned between the adjacent web plates 10 and are located below the roof sheets and spaced therefrom so that ice tongs, differential chains or other lifting devices may be easily and removably attached thereto. These longitudinal beams may be made deeper at their middles than at their ends, as shown in Figs. 5, 7 and 8. These 15 beams prevent the web plates from buckling under load, thereby securing co-operation between adjacent web plates.

15 The longitudinal beams 12 are made of a pressed U-section, which construction is very strong to sustain a load in a horizontal, vertical or diagonal direction. The upper opposite projecting flanges 13 are turned slightly upwardly so that the "ice tong" will not slip off. The beam may have an integral flange 20 14 at each end which is secured to the web plate.

25 The accompanying drawings illustrate the preferred form of the invention, though it is to be understood that the invention is not limited to the exact details of construction shown and described, as it is obvious that various modifications thereof within the scope of the claims will occur to persons skilled in the art.

30 This is a division of my co-pending application Serial No. 93,155, filed March 8, 1926, patented October 11, 1927, Patent No. 1,645,217.

I claim:

35 1. In a railway car having side plates, the combination of a plurality of carlines with their opposite ends attached to the opposite side plates, a longitudinally extending beam secured to the carlines, and roofing positioned in a plane above said beam and spaced therefrom, said beam being of U-section with an upwardly and outwardly extending flange at each upper margin thereof.

40 2. In a railway car, the combination of a longitudinally extending beam, and roofing positioned in a plane above said beam and spaced therefrom, said beam being of U-section with an upwardly and outwardly extending flange at each upper margin thereof.

45 3. In a railway car, the combination of a longitudinally extending beam positioned below the roof of the car, said beam being of U-section with an upwardly and outwardly extending flange at each upper margin thereof.

50 4. In a railway car, the combination of

a plurality of carlines with their opposite ends attached to the opposite side plates, and a longitudinally extending beam secured to the carlines, said beam being of U-section and deeper midway between the carlines and having an upwardly and outwardly extending flange at each upper margin thereof.

55 5. In a railway car, the combination of a plurality of carlines with their opposite ends attached to the opposite side plates, and a longitudinally extending beam secured to the carlines, said beam being of U-section and deeper midway between the carlines and having an outwardly extending flange at each upper margin thereof.

60 6. In a railway car, the combination of spaced apart carlines, roofing spanning the distance between adjacent carlines, and load lifting beams positioned between adjacent carlines having their opposite ends secured to adjacent carlines, said beams spaced apart from said roofing so as to provide a space for attachment of a load lifting device.

65 7. In a railway car, the combination of spaced apart carlines, roofing spanning the distance between adjacent carlines, and load lifting beams positioned between adjacent carlines having their opposite ends secured to adjacent carlines with the beams on opposite sides of a carline being in alignment to form a continuous beam, said beams spaced apart from said roofing so as to provide a space for attachment of a load lifting device.

70 8. In a railway car, the combination of spaced apart carlines, roofing spanning the distance between adjacent carlines and load lifting beams positioned between adjacent carlines having their opposite ends secured to adjacent carlines, said beams spaced apart from said roofing so as to provide a space for attachment of a load lifting beam, said beams being not lower than the bottoms of the carlines.

75 9. In a railway car, the combination of a plurality of spaced apart carlines, and load lifting beams positioned between adjacent carlines having their opposite ends secured to adjacent carlines, said beams being in alignment to form a continuous beam.

80 10. In a railway car, the combination of spaced apart carlines, and U-section load lifting beams positioned between adjacent carlines having laterally extending flanges secured to the carlines.
